UNITED STATES PATENT OFFICE.

ELIE W. LABOMBARDE, OF NASHUA, NEW HAMPSHIRE.

GLUER FOR TRAY-BOX MACHINES.

1,112,812.

Specification of Letters Patent.

Patented Oct. 6, 1914.

Application filed February 17, 1913, Serial No. 748,817. Renewed January 31, 1914. Serial No. 815,833.

To all whom it may concern:

Be it known that I, ELIE W. LABOMBARDE, a citizen of the United States, residing at Nashua, in the county of Hillsboro and 5 State of New Hampshire, have invented certain new and useful Improvements in Gluers for Tray-Box Machines, of which the following is a specification.

This invention relates to adhesive-applying mechanism, and refers particularly to 10 machines for making boxes of the type commonly known as tray boxes, the blanks having wings and tongues which are to be glued together.

The folding operation of boxes of this 15 type is materially interfered with if the glue is applied to other than the necessary and predetermined portions of the blanks. Heretofore, it has been a common practice 20 to apply the glue while the blanks are stationary. If the blanks are being supplied to the folding mechanism by continuously operating mechanism, such as endless belts, it has been customary to temporarily arrest 25 the blanks and suitable pads or other devices apply glue to the selected members or portions of the blanks. This necessarily interferes with the rapidity of operation of the machine. The means which best facilitate 30 the application of glue to the blanks has been found to consist of wheels or disks, but so far as I am aware, it has not been found practical prior to my present invention, to employ wheels or disks which will apply the 35 glue to only selected portions of the blanks.

The principal object of my present invention is to provide gluing mechanism suitable for use in connection with machines which fold tray boxes, or analogous boxes, 40 said gluing mechanism having rotary glue-applying disks or wheels, means being provided for deflecting portions of the blanks which travel past such wheels or disks, that are not to have glue applied thereto, to a 45 plane or path of movement that will prevent contact with the wheels or disks of those portions of the blanks which are to be left unglued. I will state here that I employ the word "glue" merely as a generic term 50 for any adhesive that is suitable and preferred.

My invention consists in the improvements which I will now proceed to describe and claim.

55 Of the accompanying drawings, forming a part of this specification, Figure 1 is a

plan view of so much of the mechanism as is necessary to illustrate my present improvements. Fig. 2 is a side elevation of the same.

Similar reference characters indicate the same or similar parts in both figures, numerals being employed to designate some of the parts of the mechanism, while letters are employed in connection with those portions 60 of the illustrated mechanism which particularly form the subject-matter of my present application.

The frame 20 of the machine supports a driven shaft 38, and by means of other 70 shafts, not shown, and driving and supporting pulleys, also supports a pair of carrier belts 60, 61, which travel continuously in the direction of the arrows shown in the drawings. The coöperating stretches of the 75 carrier belts 60, 61, do not grip the blanks tightly. Stop devices to aline the blanks between the carrier belts comprise arms 74 carried by brackets secured to a rock-shaft 75. An arm 76 of said rock-shaft is connected to a pitman 77 adapted to slide in a 80 suitable guide bearing 78, said pitman having a roll 79 which is actuated by a cam 80 on shaft 38, the timing of the operation of said cam being such that the stop arms 74 85 will rise and fall, keeping the position shown in Fig. 2, long enough to engage the front edge of a blank at two points on opposite sides of the central portion of the blank which is grasped by the carrier belts, so that 90 the blank, if askew, will be brought up squarely against the bent ends of the stop arms, said arms then rising and permitting the blank to be advanced by the carrier belts, with the portions *c*, *d*, *e*, of the blanks passing 95 over glue-applying disks 81 carried by a shaft 217, the lower portions of the disks rotating in a quantity of glue in a suitable receptacle 218.

In order that the blanks will be instantly 100 gripped by the belts 60, 61, after the stops 74 rise, I employ a pressing-roll 91, carried by an arm 92 of a rock-shaft 93 having a toothed segment 94 meshing with a toothed segment 95 carried by the rock-shaft 75 105 which carries the stop arms. As the cam 80 causes the rock-shaft 75 to oscillate, the segment 95 of the latter will actuate the rock-shaft 93 in a direction to cause the pressing roll 91 to bear upon the upper carrier belt 110 60 the moment that the stop arms 74 rise, so that the released blanks will be immediately

gripped by the traveling belts and caused to travel past the glue disks 81.

The particular form of blank illustrated in Fig. 1 comprises the body portion *a*, side flaps or wings *b*, corner flaps or tongues *c*, and end flaps or wings *d*. With this particular form of blank it is necessary that glue be applied only to the flaps or wings *d*, and not to the corner tongues *c*. Of course, with the construction so far described, the blanks, as they travel beyond the position shown in Fig. 1, would have stripes of glue applied to all of the projecting portions at each end of the blank. To select the end portions which shall have glue applied thereto, or in other words, to deflect or divert away from the glue disks those portions which are not to have glue applied thereto, I employ a pair of deflector arms *g* which are carried by arms *h* depending from a rock-shaft *i* mounted in standards *k*, said rock-shaft having an arm *l*. A spring *m* coiled upon the shaft *i* and engaging the arm *l* and one of the standards *k*, has a tendency to normally hold the rock-shaft and the deflector arms *g* in the position shown in Fig. 2, in opposition to the cam presently described. To the arm *l* is connected the upper end of a pitman *n*, the other end of said pitman having a yoke *o* bestriding shaft 38, and having a roll *p* which is acted upon by a cam *q* carried by said shaft 38.

The cams *q* and *q* are so shaped and positioned relatively to each other that during the operation of the machine, just after the blank reaches the temporarily arrested position shown in Fig. 1, the arms *g*, the tips of which are then under two of the corner tongues *c*, will swing upwardly and somewhat rearwardly, thus lifting those two corner tongues. Immediately following this the stop arms 74 rise and the starting roll 91 descends, so that the blank is pinched tightly enough between the traveling carriers 60, 61, to advance the blank with the end flaps or wings *d* passing under the arms *g*. It will be noticed that the depression of the cam *q* is quite short. This causes the arms *g* to immediately swing back to the position shown

in Fig. 2. The end flaps or wings *d* are now under the arms *g* and will contact with the peripheries of the glue disks, but since the other two corner tongues *c* naturally retain their positions in the plane of the carrier belts, said other two corner tongues *c* will ride on top of the arms *g*, and, therefore, have no glue applied thereto.

It will now be understood that I have provided automatically operating deflectors which divert portions of the blank so that they travel in a plane out of the plane of the surface of the glue disks, the end flaps or wings *d* being selected as the ones which are permitted to have glue applied thereto.

I claim:—

1. Mechanism for applying an adhesive to selected portions of box blanks, comprising an adhesive applicer, means for carrying a blank past said applicer, and a deflector for diverting a portion of the blank into a path of travel out of the plane of the applicer.

2. Mechanism for applying an adhesive to selected portions of box blanks, comprising a carrier for the blanks, guiding mechanism for causing different portions of the blanks to travel in different planes, and means for applying an adhesive to the portions traveling in one of said planes.

3. Mechanism for applying an adhesive to selected portions of box blanks, comprising a carrier for the blanks, rocking arms for deflecting portions of said blanks, and means for applying an adhesive to the portions of the blanks which are not deflected.

4. In mechanism of the character described, the combination with a glue wheel, of means for feeding blanks past said glue wheel, a deflector, and means for operating said deflector to cause it to divert a selected portion of the blank to cause it to move past the glue wheel without contact therewith.

In testimony whereof I have affixed my signature, in presence of two witnesses.

ELIE W. LABOMBARDE.
